(57) **CLAIM**

The ornamental design for a toy panel, as shown and described.

DESCRIPTION

FIG. 1 is a top perspective view of a toy panel showing an embodiment of the design of this invention.

FIG. 2 is a top view thereof.

FIG. 3 is a bottom view thereof.

FIG. 4 is a front view thereof.

FIG. 5 is a rear view thereof.

FIG. 6 is a left side view thereof.

FIG. 7 is a right side view thereof.

FIG. 8 is a perspective view showing the toy panel of FIG. 1 interconnected with an identical environmental panel.

FIG. 9 is a perspective view showing the toy panel of FIG. 1 interconnected with an identical environmental panel.

FIG. 10 is a perspective view showing the toy panel of FIG. 1 interconnected with an identical environmental panel.

FIG. 11 is a perspective view showing the toy panel of FIG. 1 interconnected with identical environmental panels.

FIG. 12 is a perspective view of a toy panel, showing an alternative embodiment of the design.

FIG. 13 is a top view of the embodiment shown in FIG. 12.

FIG. 14 is a bottom view of the embodiment shown in FIG. 12.

FIG. 15 is a front view of the embodiment shown in FIG. 12.

FIG. 16 is a rear view of the embodiment shown in FIG. 12.

FIG. 17 is a left side view of the embodiment shown in FIG. 12; and,

FIG. 18 is a right side view of the embodiment shown in FIG. 12.

The evenly spaced broken lines depict environmental subject matter, are shown for illustrative purposes only and form no part of the claimed design.

The line-dot-line broken lines depict environmental and optional indicia and form no part of the claimed design.

1 Claim, 7 Drawing Sheets
